R. E. CURTIS

PISTON JIG

Filed June 9, 1923

R. E. Curtis, INVENTOR:

C. C. Kimes,

ATTORNEY.

UNITED STATES PATENT OFFICE.

ROSS E. CURTIS, OF LINCOLN, KANSAS.

PISTON JIG.

Application filed June 9, 1923. Serial No. 644,418.

To all whom it may concern:

Be it known that I, Ross E. CURTIS, a citizen of the United States, residing at Lincoln, in the county of Lincoln and State of Kansas, have invented new and useful Improvements in Piston Jigs, of which the following is a specification.

This invention relates to a piston jig, or device for use in holding a piston while removing and replacing bushings, reaming and alining set bushings, and performing other similar work upon pistons of internal combustion engines and other similar pistons.

One object of the invention is to provide a jig which will receive the piston and form a firm support all around the piston, while piston bushings are being removed or applied, reamed or alined, thus protecting the thin walls of the piston against any possibility of excessive distortion or breakage while work of the stated character is being performed.

Another object of the invention is to provide a jig which is positive in its action in holding a piston at right angles to the travel of a press arbor or reamer, and parallel to the surface of the face plate on a press, so as to ensure perfect alinement with the press arbor or the production of a perfectly alined pair of bearings in reaming.

The invention consists of the features of construction, combination and arrangement of parts, hereinafter fully described and claimed, reference being had to the accompanying drawing, in which:—

Figure 1 is a view, partly in side elevation and partly in section, of a piston jig embodying my invention.

Figure 2 is a vertical transverse section on the line 2—2 of Figure 1.

Figure 3 is a top plan view of the jig.

Figure 4 is a vertical longitudinal section through the jig, showing a piston fitted therein.

In carrying my invention into practice, I provide a piston jig 1 comprising a cast iron frame in the form of a cylindrical band adapted to receive and completely enclose a piston of a given size. This cylindrical band is open at each end and provided with a smooth turned internal surface 2 concentric with the horizontal center of the cylinder which is to be fitted therein. This surface 2 may be of a required radius

to permit an over-sized piston to enter the jig, the construction described allowing a piston to be entered or removed from either end of the jig, as will be readily understood. 60

The cylinder or band 1 has a base portion 3 formed with a flat surface 4 designed to rest firmly and squarely upon a work bench or table. The surface 4 is parallel with the horizontal center of the jig and provided at opposite sides with extension flanges 5 having slots or notches 6 for the passage of bolts or other suitable fastenings whereby the jig may be secured to the work bench or table. Reinforcing webs 7 connect these flanges with the base portion of the cylinder wall 2, at the sides thereof, thus strengthening the jig cylinder so as to adapt it to effectually withstand all pressures and strains falling thereon. 75

Formed in the top and bottom of the cylinder 2, centrally thereof, are openings 8, arranged in axial alinement with each other and with the vertical center of the cylinder, which openings are provided for registry with the bushings and bushing openings of a piston fitted within the cylinder, thus exposing the bushings and their receiving openings to permit the required work to be performed thereon. 85

In the practical use of the device, it is bolted or otherwise firmly secured to a bench or work table so that the horizontal axis of the cylinder 1 lies parallel with the surface of the work bench or table, the bottom opening 8 in the jig being arranged in alinement with a corresponding opening in the table below. The piston 9 to be operated upon may be inserted into the jig, as shown in Figure 4, from either end thereof, and is brought into position so that the bushing receiving portion 10 and bushings 11 accurately register with the openings 8. When the piston is thus inserted, it is entirely surrounded by the band 2 and firmly braced and sustained thereby, allowing old bushings to be driven out and new bushings driven in without liability of straining, distorting or cracking the comparatively thin walls of the piston. 90

When the piston is so held it will be disposed parallel with the face plate of the press so as to allow the arbor of the press to come in accurate contact with the bushings. In the operation of removing old bushings, it will be understood that the bushings may be forced out of their receiving openings and discharged through the 105

bottom opening 8 and through the registering opening in the table or work bench. When the jig is so disposed, also, a piston contained therein will be held accurately 5 at right angles to the travel of a reamer, allowing the reaming operation to be carried on so as to ensure a perfectly alined pair of bearings.

The band 1 may be longitudinally split 10 at one side, as indicated at 12, so as to adapt it for expansion and contraction to receive pistons of varying sizes within certain limits. Apertured lugs 13 are provided upon the meeting edges of the split portion for passage of bolts 14 carrying winged nuts 15 whereby the band may be contracted as desired and held in such condition. The metal of which the band is made in practice will, of course, be of sufficient resiliency to adapt 20 it to expand to major diameter when the bolts are slackened, the tightening of the bolts resulting in the contraction of the band to smaller diameters within given limits. This construction will allow regular and 25 oversize pistons of varying diameters, within certain degrees, to be received and braced for the purposes described.

From the foregoing description, taken in connection with the drawing, the construction 30 and mode of operation of my improved piston jig will be readily understood, and it will be seen that a device of the character described is provided which is simple of construction and adapted to effectually support and brace the piston while bushings are 35 being removed and replaced or being reamed

or while other similar work is being performed, thus allowing the work to be carried on without liability of cracking or otherwise injuring the piston.

Having thus fully described my invention, I claim:

1. A piston jig for use in applying, removing and reaming piston bushings, said device comprising a body adapted to snugly 45 embrace and sustain the walls of the piston throughout the extent of the latter during bushing applying, removing and reaming operations, said body having openings to aline with the bushing receiving openings 50 in the piston.

2. A piston jig for use in applying, removing and reaming piston bushings, said device comprising a body having a circular wall concentric with the axis of a piston to 55 be operated upon and adapted to surround and snugly engage the outer walls of the piston during bushing applying, removing and reaming operations, and having a substantially flat base approximately parallel 60 with the horizontal center of the surrounded piston, said body being provided with alined openings in its top and base being in axial alinement with each other and with the vertical center of the body to register with 65 the bushing receiving openings in the piston.

In testimony whereof I affix my signature in presence of a witness.

ROSS E. CURTIS.

Witness:

W. M. WILSON.
